UNITED STATES PATENT OFFICE.

JOHN A. JONES, OF ROME, NEW YORK.

EGG-CRATE.

1,153,495.

Specification of Letters Patent. Patented Sept. 14, 1915.

Application filed November 24, 1914. Serial No. 873,786.

To all whom it may concern:

Be it known that I, JOHN A. JONES, a citizen of the United States, residing at Rome, in the county of Oneida and State of New York, have invented new and useful Improvements in Egg-Crates, of which the following is a specification.

This invention relates to shipping crates and contemplates the provision of a crate primarily intended for use in the transportation of eggs.

The general object of the invention is to provide a novel construction of a crate of the above mentioned character wherein the eggs are yieldably supported individually in spaced relation to each other to avoid breaking or other injury thereof during their transportation.

Other objects will appear from the following description considered in connection with the accompanying drawings wherein like numerals of reference indicate similar parts in the several views and in which:

Figure 1 is a top plan view of the crate. Fig. 2 is a front elevation. Fig. 3 is an end elevation. Fig. 4 is a vertical sectional view taken on line 4—4 of Fig. 1. Fig. 5 is a perspective view of one of the upper and lower members of the nest sections. Fig. 6 is a view of the upper section of the paper cup. Fig. 7 is a view of the lower section thereof. Fig. 8 is a view of one of the expandable rings. Fig. 9 is a view showing the hinged connection between the rear walls of the crate sections.

The crate essentially consists of an upper and lower box-like section 5 and 6 respectively, each section comprising a wire frame structure 7, including spaced parallel side and end bars 8, the upper section including a top 9 and the lower section the bottom 10 of the crate. The side and end walls are similarly constructed from wire, which may be of any suitable mesh and connected to the spaced parallel bars 8 constituting the frames 7. As shown in this particular instance they comprise the diamond-shaped members 11 connected by the links 12. The adjacent bars 8 of the front wall of each section are offset inwardly as at 13 to permit certain of the links 12 of the upper and lower sections 5 and 6 respectively, which are detachably engaged as at 14 to allow the upper section 5 to be raised, to lie in the plane of the front walls of the crate. The rear walls of the section are hingedly con-

nected together in any suitable manner, preferably by means of the hook and eye connection 14' as shown in Fig. 9, the adjacent bars of the rear wall being offset in a manner similar to the offset portions of the bars 8 of the front wall, to permit the hinge connection to lie in the same plane with the walls of the crate. The top and bottom 9 and 10 respectively are similarly constructed from wire and comprise a series of spaced longitudinally and transversely extending bars 15, and a plurality of ring-like members 16 supported in spaced relation to each other and to the bars 15 by means of the divergently disposed arms 17, the latter having one end fastened to the bars 15 in the manner shown. As the nests for the eggs are supported by these rings, there may be as many rings employed as desired, this of course depending wholly upon the desired size of the crate. As will be obvious from the drawings, the eggs are individually supported within these nests in spaced relation to each other, to avoid all possibility of the eggs being broken or cracked by coming in contact with each other during their transportation, or under any other circumstances.

Each nest comprises two sections, an upper section carried by the top 9 of the crate and a lower section carried by the bottom 10 thereof, while each of the nest sections consist of four resilient similarly constructed fingers 20 disposed in alinement and extending within the crate from the ring-like members 16 at diametrically opposite points. Each of the fingers 20 preferably consists of a flat piece of resilient metal having one end looped around the ring-like members 16 as at 21, and their body portions 22 oppositely curved throughout their length, so that when the nest sections are superimposed as shown in Fig. 4, each pair of fingers 20 conform to the shape of the egg. This curvature of the fingers 20 together with the offset portions 23 formed therein permit said fingers, when the eggs are nested, to have a slight vertical and lateral movement to compensate for any rough handling the crate may be subjected to during the transportation. The fingers 20 are of a length to engage approximately one-half of the egg, so that when the nest sections are operatively associated, the free ends of the fingers of the respective sections engage each other at approximately the transverse center of the egg. The free ends of the fingers 20 of the upper nest sections

are flanged as at 24, the latter being engaged by the upwardly extending flange 25 formed by the free ends of the fingers of the lower nest section for the purpose to be hereinafter described. The body portions of the fingers 20 are formed with horizontally disposed alined offsets 26 providing spaced circumferential series thereof, which receive the expandible rings 27. These rings as shown 10 in Fig. 8 are formed at diametrically opposite points with resilient offset portions 28 there being four of these offsets, one of each being snugly fitted in the offsets 26 of the fingers 20. The purpose of these rings 27 is 15 to retain the fingers 20 operatively associated to hold an egg with a minimum amount of pressure against the walls of the egg, and to allow the fingers to expand and contract to accommodate different sizes of eggs.

20 Arranged in each of the upper and lower nest sections, is a section 29 of a paper cup, in which the eggs are placed, the adjacent edge of each of the cup sections being formed with a circumferential flange 30 held in contact with each other by means of the flanges 24 and 25 of the nest fingers 20 as clearly shown in Fig. 4.

In the use of the crate, the paper cup sections 29 are first arranged in the upper and 30 lower nest sections. The eggs are then placed in the lower sections of the cups, and as the upper section 5 of the crate is swung to closed position, the upper sections of the cups and nest sections receive the upper half 35 of the eggs, and at the same time the flanges 30 of the paper cups are effectively clamped between the flanges 24 and 25 of the fingers 20. The upper and lower sections of the 40 crate 5 and 6 respectively are then locked by means of the links 12 as clearly shown in Fig. 2.

In the space between the top and bottom 9 and 10 respectively and the bars 8 of the frame 7 is placed a suitable piece of cardboard 31 or other packing material, the same being also arranged against the inner face of the side and end walls as shown.

Manifestly with a crate constructed in the above described manner, eggs may be shipped 50 without any possibility of becoming broken or injured irrespective of any rough handling which the crate may be subject to during transportation.

It is believed that from the foregoing description 55 the nature and advantages of the invention will be readily understood without requiring a more extended explanation

and therefore the same has been omitted. However I desire to have it understood that 60 various changes in the construction and arrangement of parts may be resorted to when desired as fall within the scope of the appended claims.

What I claim is:

1. A wire egg crate comprising an upper 65 and lower box-like section, coöperating nest sections projecting inwardly from the top and bottom of the crate, each of said nest sections including a plurality of resilient curved fingers, said fingers having alined offsets, expandible rings arranged within said offsets, and means for locking said crate sections together.

2. An egg nest comprising superimposed 75 sections, each of said sections including a plurality of diametrically opposed resilient fingers, each of said fingers having alined offsets, and an expandible ring having offset portions arranged within the offsets of said fingers.

3. An egg nest comprising superimposed 80 sections, each of said sections including a plurality of curved resilient fingers disposed in diametrically opposed relation, a paper cup section arranged in each section, and expandible rings encircling the fingers of each section as and for the purpose described.

4. An egg nest comprising superimposed 85 sections, each of said sections including a plurality of curved resilient fingers disposed in diametrically opposed relation, a flanged paper cup section arranged in each of the nest sections, the adjacent ends of said fingers being flanged to clamp the flanges of the cup sections therebetween, and an expandible ring encircling the fingers of the section and secured thereto as and for the purpose described.

5. A wire egg crate comprising an upper 90 and lower box-like section, ring-like members supported from the top and bottom thereof, nest sections carried by said rings and including a plurality of diametrically opposed resilient curved fingers, each of said fingers having alined offset portions, an expandible ring supported in said offsets, and means for locking said crate sections together.

In testimony whereof I affix my signature in presence of two witnesses.

JOHN A. JONES.
